(57) **CLAIM**

The ornamental design for a rack as shown and described.

DESCRIPTION

FIG. 1 is a front elevational view of a rack showing my new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;

FIG. 7 is a top perspective view thereof; and,
FIG. 8 is a top perspective view showing the rack in a
disassembled state.
The broken lines in the drawings illustrate portions of the
rack which form no part of the claimed design.

1 Claim, 8 Drawing Sheets
